UNITED STATES PATENT OFFICE.

BRADFORD LESLIE, OF LONDON, ENGLAND.

JOINT FOR RAILWAY-RAIL ENDS.

Application filed February 13, 1924. Serial No. 692,535.

To all whom it may concern:

Be it known that I, BRADFORD LESLIE, a subject of the King of Great Britain, residing in London, England, have invented a certain new and useful Improved Joint for Railway-Rail Ends, of which the following is a specification.

This invention relates to an improved joint for connecting and supporting the square ends of railway rails and is adaptable to all types of such rails.

The object of the present invention is to provide an inflexible support for the rail ends at each joint in order to preserve their running surfaces in the same plane, in substitution for the ordinary fish-joint and other joints which have been found to rest upon sleeper area insufficient to compensate for the non-continuity of the rails, resulting in low joints which produce wear and concussion.

It has been proposed to provide a central transverse sleeper at the joint between the two transverse sleepers on either side of the joint and in a known construction intended to supersede the fish-joint the rail ends are carried upon a bearing plate supported upon the aforesaid sleepers and said rail ends fastened to the bearing plate by means of clamping plates.

According to the present invention the defects of the fish-joint and other joints are remedied by the provision of an inflexible sleeper platform consisting of a joint block under each rail joint rigidly connected with additional supporting blocks on either side, which blocks may be transverse sleepers extending under both rails, the platform so formed having bearing surface on the ballast adequate to compensate for the non-continuity of the rails and supporting the rails normally at the joint upon cast iron chairs (in the case of bull-headed or reversible rails) and upon bearing plates (in the case of flat footed rails) carried upon the inflexible sleeper platform.

In one construction according to the invention the joint block extends longitudinally between and preferably at the same level as two transverse sleepers one on either side of the joint, and is firmly secured to the sleepers as by means of tongue plates in contiguous portions and adjustable tie rods between the two sleepers. In an alternative construction the inflexible support for the rail ends at each joint is afforded by

three or more short contiguous transverse sleepers fixed to an iron joist or beam of such a section as to prevent any appreciable deflection under maximum axle load at the joint.

The result is a platform supporting the rail ends normally to the vertical load having the inflexibility necessary to preserve the running surfaces of the rail ends in a common plane and an effective bearing surface on the ballast which compensates for the non-continuity of the rails. This bearing surface is about one-third, or more, greater than that secured in usual practice.

In the accompanying drawings Fig. 1 is a plan view of the improved joint as adapted to bull-head or reversible rails; Fig. 2 is a section on the line 2-2 of Fig. 1; Fig. 3 is a plan view of the improved joints as adapted to rails having a flat foot or base; and Fig. 4 is a section on the line 4-4 of Fig. 3.

Referring to Figs. 1-4, the inflexible support for the rail ends consists of a short longitudinal sleeper or joint block A combined with the transverse sleepers B, one on either side of the joint, said longitudinal sleeper or joint block extending between and preferably at the same level as the transverse sleepers B and being rigidly connected therewith by means of tongue plates L or in any other suitable manner.

The longitudinal sleeper or joint block A is held in firm contact with the transverse sleepers B by means of bolts C which are adapted to be screwed up tightly and prevent movement between the sleepers. The longitudinal sleeper or joint block would be preferably wider than the transverse sleepers and arranged so that the whole platform is readily accessible from all sides and constitutes an inflexible support for the rail ends.

In the case of bull-head or reversible rails, see Figs. 1 and 2, the rails D are carried in cast iron joint chairs E fastened to the longitudinal sleeper A by means of screws M, the bases of which chairs are wide enough to afford support to the rails. The jaws of the joint chairs may be increased in width if desired.

Hard wood or other suitable wedges F may be interposed between the jaws of the chairs and the rails to hold them in position. If holding wedges are used, when adjustment has been made to permit of expan-

sion or contraction of the rails, these wedges may be secured by pins passing through holes in the key jaw G of the chair, and in the wedges to prevent the latter from working loose. This latter device may be used on the intermediate sleepers, and if the wedges are hard-driven before pinning at two or three sleepers on either side of the centre of the rail, they will prevent creep 10 of the rails. The use of such joint chairs dispenses with the necessity for holes in the rails.

In the case of rails having a flat base or foot, see Figs. 3 and 4, holes in the rails are 15 also unnecessary. The rail ends D are supported normally upon a metal bearing plate H of suitable thickness, which is fastened directly to the longitudinal sleeper or joint block A by means of screws I and dog-spikes 20 J which pass through holes in the bearing plate, each of said screws being provided with a collar K which is adapted to overlap the rail flange and hold the rail in contact with the bearing plate.

25 The transverse sleepers B may also have bearing plates H interposed between them and the rails, or these latter bearing plates may be formed integral with the aforesaid longitudinal bearing plate.

30 The bearing plates H are preferably rolled to give the usual cant to the rails, as shown in Fig. 4, thereby dispensing with the need for adzing the transverse sleepers and, in the case of a joint chair, the base of 35 the chair is cast at the inclination required to give the cant.

Having thus described the nature of the said invention and the best means I know of carrying the same into practical effect, I 40 claim:—

1. An inflexible support for the ends of railway rails designed to preserve their running surfaces in the same plane without the use of fishplates, comprising a sleeper plat-

form consisting of a joint block, additional 45 supporting blocks on either side of said joint block, means rigidly connecting the joint block with the adjacent supporting blocks to maintain the surfaces thereof at the same level, said means including tie 50 bolts passing through said supporting blocks, and a bearing plate secured centrally upon the said joint block and supporting the abutting ends of the rails at their junction and for a distance on either side there- 55 of.

2. An inflexible support for the ends of railway rails, comprising a joint block for disposition longitudinally under a rail joint, transverse sleepers, one on either side of the 60 joint block, having their surfaces at the same level as that of the joint block, means connecting said joint block and said transverse sleepers to maintain the surfaces at the same level, and tie bolts connecting the transverse 65 sleepers and operating to press their sides firmly against the ends of the joint block.

3. An inflexible support for the ends of railway rails, comprising a sleeper platform for a rail joint consisting of a joint block 70 to be placed under a rail joint, additional supporting blocks on either side of said joint block, mortised connections between the joint block and the additional supporting blocks and tie bolts passing through the 75 said additional supporting blocks.

4. An inflexible support for the ends of railway rails, comprising a sleeper platform for supporting a rail joint consisting of a joint block to be placed under a rail joint, 80 two transverse sleepers, one on either side of the joint block and at the same level there-with, tongue plates connecting the joint block with the adjacent sleepers, and tie bolts passing through the said sleepers. 85

In testimony whereof I have signed my name to this specification.

BRADFORD LESLIE.
